(57) **CLAIM**

The ornamental design for a battery pack as shown and described.

DESCRIPTION

FIG. 1 is a bottom right rear perspective view of a first embodiment of a battery pack showing our new design.

FIG. 2 is a top left front perspective view of the battery pack of FIG. 1.

FIG. 3 is a bottom plan view of the battery pack of FIG. 1. FIG. 4 is a rear elevation view of the battery pack of FIG. 1.

FIG. 5 is a right side elevation view of the battery pack of FIG. 1.

FIG. 6 is a front elevation view of the battery pack of FIG. 1.

FIG. 7 is a top plan view of the battery pack of FIG. 1.

FIG. 8 is a left side elevation view of the battery pack of FIG. 1.

FIG. 9 is a bottom right rear perspective view of a second embodiment of a battery pack showing our new design.

FIG. 10 is a top left front perspective view of the battery pack of FIG. 9.

FIG. 11 is a bottom plan view of the battery pack of FIG. 9. FIG. 12 is a rear elevation view of the battery pack of FIG. 9.

FIG. 13 is a right side elevation view of the battery pack of FIG. 9.

FIG. 14 is a front elevation view of the battery pack of FIG. 9.

FIG. 15 is a top plan view of the battery pack of FIG. 9; and, FIG. 16 is a left side elevation view of the battery pack of FIG. 9.

In the drawings, the broken lines depict portions of the battery pack that form no part of the claimed design.

1 Claim, 6 Drawing Sheets
